UNITED STATES PATENT OFFICE.

MILTON C. PETERS, OF OMAHA, NEBRASKA.

ROTARY CUTTER.

1,013,611.

Specification of Letters Patent.

Patented Jan. 2, 1912.

Application filed November 10, 1910. Serial No. 501,567.

To all whom it may concern:

Be it known that I, MILTON C. PETERS, a citizen of the United States, residing at Omaha in the county of Douglas and State 5 of Nebraska, have invented certain new and useful Improvements in Rotary Cutters, of which the following is a specification.

This invention relates to certain new and useful improvements in rotary cutters, or 10 machines for disintegrating or reducing material.

Primarily, the machine is designed for reducing alfalfa-hay, prairie-hay, corn products or any like material, and also for cutting excelsior, paper, hair, moss, wool, cotton or similar fibrous substances, and also continuously and simultaneously separating the fine reduced material from the coarser material requiring further reduction.

20 The essential object of the invention is to simplify machines of this general class and to render the cutting mechanism of these machines more effective by arranging the same so that the cutters act more efficiently to shred, tear and cut the material by a shearing operation; and the invention consists of the parts and the constructions, arrangements and combinations of parts which I will hereinafter describe and claim.

30 In the accompanying drawings forming part of this specification and in which similar reference characters indicate like parts in the several views: Figure 1 is a vertical, longitudinal sectional view of a rotary cutter embodying the salient features of my invention. Fig. 2 is an enlarged side elevation of one of the knife-carrying hubs detached. Fig. 3 is a vertical sectional view on the line X—X of Fig. 2. Fig. 4 is a 40 detail in plan view of one of the cutting blades. Fig. 5 is a part side elevation and part sectional view of the cutting blade of Fig. 4. Fig. 6 illustrates a plurality of the hubs and cutting blades arranged side by side on the driving shaft.

45 In carrying out my invention I mount the machine upon a suitable bed or foundation, A, and I construct the main frame or casing with parallel sides, B, and connecting back 50 and top plates, C, so as to form substantially an inclosed chamber in which the rotary cutter operates, the sides of the frame or casing and also the top being extended in a forward direction, as at D, to form substantially an inclosed feeding chamber, supplied with complementary feeding devices,

which chamber is open at the front to permit the admission to the feeding devices of the material to be reduced.

In the herein illustrated embodiment of 60 my invention, the material is fed to the receiving chamber of the casing or frame by means of an endless conveyer-belt, E, which is horizontally disposed and passes over suitable end drums, e, e', one of which has its 65 journal boxes, e², adjustably mounted on a horizontal frame or support, F, whereby the tension of the belt may be regulated.

Various means may be employed for securing the adjustment noted in Fig. 1. I 70 disclose for the purpose the horizontal screws, G, having many-sided outer ends adapted for the reception of a wrench or like tool.

Within the receiving chamber of the 75 frame or casing and mounted in the sides thereof over the delivery end of the conveyer-belt, E, are suitable feed rolls H, the innermost one of which is shown as having its shaft, h, mounted in journal boxes, h', to 80 which are connected vertical screws, h², whereby said roll may be raised and lowered relatively to the carrying surface of the belt and according to the nature of the material undergoing treatment. The feed-rollers 85 may be of any approved type; they are herein shown as being armed with rows of peripheral teeth that they might the more efficiently engage the hay, or other material, and positively feed it to the cutting devices, 90 hereinafter described.

On the outer ends of the shafts, h, of the feed rolls are secured sprocket-wheels, 5, around which passes a sprocket chain, 6, for operating the rolls in the same direction, the 95 said sprocket-wheels and chain being shown by dotted lines in Fig. 1.

It will be observed that the receiving chamber in which the rolls operate, is substantially an inclosed chamber, this being 100 desirable as tending to the elimination of the objectionable presence of dust, exterior to the machine. To better provide for this function of the machine, the top of the casing is pierced with an opening, 8, to which 105 a pipe or connection, not shown, from a suitable suction or blast may lead, for conducting the dust and fine particles to any suitable receiver or machine.

It might also be here remarked that the 110 top or cover portion of the casing may be provided with sections, 9 and 10, say one for

the receiving chamber of the casing and the other for the cutting chamber hereinafter mentioned, which sections are hinged at 11 and 12, whereby access may be had to the 5 chambers and to the feed-rolls and, rotary cutter.

The leading feature of my invention is the construction and arrangement of the parts constituting the rotary cutter and 10 which feature I will now describe. This cutter consists of a series of hubs, 13, placed side by side upon the shaft, 14, and fixed thereto, each of said hubs comprising a hub-portion, 15, and outwardly extending arms, 16. By reference to Fig. 3, it will be seen that the outer end of each arm 16, is widened to form a broad flat seat, 17, for the blades or cutters, 18.

The widened seat portions are trans- 20 versely inclined as shown, the inclination given the blade or cutter being common to all the blades or cutters of a particular hub-member. In practice, I have attained the best results by placing the hubs in position 25 on the shaft, 14, in such manner that the blades or cutters of alternate hubs incline oppositely to the cutters of adjacent hubs. In other words if the cutters or blades of the first hub incline to the right, 30 the blades or cutters of the next hub will incline to the left, as illustrated in Fig. 6.

The blades are spaced apart around the circumference of the rotary cutter and the hubs are so set on the shaft relatively to 35 each other that the blades of alternate hubs substantially register with the spaces between the contiguous blades of adjacent hubs, the combined edges of each row of cutters thus formed producing an efficient 40 cutting medium for any material of the character before described coming into the range of action of the blades and a suitable stationary cutter-bar.

The blades, 20, consist of pieces of steel 45 or other suitable material of substantially the form of a parallelogram; that is each blade represents substantially a right-lined quadrilateral figure, whose opposite edges are parallel and equal. The disposition of 50 the blades is such, however, that the side edges of each blade stand parallel with each other and in a plane which is at right-angles to the shaft, 14, or the axis about which the hubs rotate, while the cutting 55 edges extend at an incline from one side edge of a blade to the other side edge thereof. Each blade has its opposite inclined edges beveled to form a cutting edge, and the bevel of one is reversed or opposite to 60 that of the other edge, whereby the blade may be reversed and either cutting edge employed for the disintegration of the hay or other material. Further, each blade is provided with one or more elongated slots, 65 21, through which bolts, 22, pass to re-

movably secure the blade to the broad seat portion provided at the outer ends of the arms, 16.

By the arrangement described, the combined blades form what might be termed a 70 continuous cutter of individual sections each operating with a shearing action to divide the hay or material passing over the stationary cutter-bar. The number of blades carried by each hub, the number of 75 hubs arranged side by side and the means employed for securing the blades to the arms, 16, may be varied to meet the size and capacity of the machine or to satisfy the desire or requirements, without departing 80 from the scope of the invention.

The stationary cutter-bar, 23, is fixed to the frame or casing at the inlet to the chamber in which the rotary cutter operates; it is shown as substantially rectangular in 85 cross-section so that it may be reversed to present a new cutting edge to the action of the blades of the rotary cutter, when the edge previously used has become dull.

The chamber in which the cutter rotates 90 is inclosed by a curved screen, 24, of suitable material and the material divided by the action of the movable blades and stationary cutter-bar, enters the chamber and the particles fine enough pass through the meshes 95 or perforations in the screen and are received into an underlying hopper, 25, and thence directed through an opening, 26, in the bottom of the frame or casing and may be conducted to any desired point of de- 100 posit.

The material of which the screen is composed includes any material commonly used for screening purposes, said screen being supported and secured in place by means of 105 angle-bars, 27, or like flanged members bolted to the inside of the casing. Other forms of members capable of disintegrating or reducing material may be used in place of the blades shown and described and without disturbing the arrangement of separate hubs disposed side by side on a common shaft; the said members however, are designed to each rotate in a circular path slightly different to the one immediately preceding it, and the character of the final product depends upon the adjustment of the blades relatively to the stationary cutter-bar, the size of the meshes or openings in the screen, and whether the material acted 110 on is wet or dry.

Power to operate the machine is transmitted by a belt, 30, to a band wheel, 31, on the shaft of the rotary cutter, which shaft also carries a small pulley, 32, from which a crossed-belt, 33, extends to a large pulley, 34, on the shaft, 35. A pinion, 36, on the shaft, 35, meshes with a large gear-wheel, 37, on the shaft, 38, and a pinion, 39, on said shaft, 38, engages a gear-wheel, 40, 125 130

which in turn drives a pinion, 41, on the shaft of one of the drums, *e*, around which the belt conveyer, *E*, passes. From the shaft, 38, a sprocket chain, 42, extends to one of the feed rolls, while a second sprocket chain, 43, connects these rolls so that they rotate in the same direction. This train of operating gears is no essential part of the invention and is only shown diagrammatically.

Having thus described my invention what I claim as new and desire to secure by Letters Patent, is:

1. The combination with a casing, a fixed cutter bar, and a radial shaft, of a cutter having a plurality of series of blades arranged side by side upon said shaft, the blades of each series being transversely inclined and the blades of alternate series being inclined oppositely to those of the series upon each side thereof, each of said blades having a cutting edge substantially parallel with said axis.

2. The combination with a casing, a fixed cutter-bar, and a radial shaft, of a cutter consisting of a series of hubs arranged side by side upon said shaft, each of said hubs carrying an annular series of spaced blades, the blades of each series being transversely inclined and the blades of alternate hubs being arranged transversely in line with the spaces between adjacent blades of contiguous hubs, said blades having their cutting edges substantially parallel with the axis of the hubs.

3. The combination with a casing, a fixed cutter-bar, and a rotary shaft, of a cutter consisting of a series of rotatable hubs arranged in substantially close order side by side upon said shaft, each of said hubs having outwardly extending arms, and cutting blades fixed to the outer ends of the arms and spaced apart and arranged in annular series so that they successively sweep past the edge of the fixed cutter-bar, the blades of each hub being transversely inclined in the same direction and the blades of alternate hubs being oppositely inclined and arranged transversely in line with the spaces between adjacent blades of a contiguous hub on each side thereof.

4. A rotary cutter having a plurality of series of blades fashioned in the form of a parallelogram and turnable about a common axis, the blades of each series being

transversely inclined and the blades of alternate series being inclined oppositely to those of the series upon each side thereof, each of said blades having front and rear edges inclined from one side to the other and being beveled to form a plurality of cutting edges, and means whereby the blades are reversibly secured.

5. The combination with a casing and a fixed cutter-bar, of a shaft extending transversely across the casing, a series of hubs arranged in substantially close order side by side on said shaft, each of said hubs having a plurality of outwardly extending arms spaced apart at their outer ends, and having said ends formed with widened transversely inclined portions, blades fixed to said transversely inclined portions of the arms and so arranged that the blades carried by one hub stand transversely in line with the spaces between adjacent blades of contiguous hubs, the blades of alternate hubs being transversely inclined in an opposite direction to the blades of intermediate hubs.

6. The combination with a casing having an internal screen chamber and a stationary cutter-bar, of a rotary cutter operable in said chamber and consisting of a series of hubs arranged side by side upon a common axis, and having transversely inclined blades spaced apart around the circumference, the cutters of alternate hubs being inclined oppositely to those of intermediate hubs and standing transversely in line with the spaces between adjacent blades of said intermediate hubs.

7. The combination with a casing having an internal screen chamber and a stationary cutter-bar, of a rotary cutter operable in said chamber and consisting of a series of hubs arranged side by side upon a common axis, and having transversely inclined blades spaced apart around the circumference, the cutters of alternate hubs being inclined oppositely to those of intermediate hubs and standing transversely in line with the spaces between adjacent blades of said intermediate hubs, said blades having substantially the form of a parallelogram.

In testimony whereof I affix my signature in presence of two witnesses.
